UNITED STATES PATENT OFFICE.

WALTER W. LIND, OF EAST ORANGE, NEW JERSEY.

SAD-IRON.

979,520.

Specification of Letters Patent. Patented Dec. 27, 1910.

Application filed January 28, 1910. Serial No. 540,545.

To all whom it may concern:

Be it known that I, WALTER W. LIND, a citizen of the United States, and a resident of East Orange, in the county of Essex and 5 State of New Jersey, have invented certain new and useful Improvements in Sad-Irons, of which the following is a specification.

The invention relates to improvements in sad-irons of the so-called self-heating class, 10 and it consists in the novel features and combinations of parts hereinafter described, and particularly pointed out in the claims.

The iron of my invention comprises a lower part which is hollow and designed to 15 contain a suitable fuel for keeping the iron hot, and an upper part carrying the handle and adapted to be placed downwardly upon and be detachably secured to said lower part.

20 The object of my invention is generally to increase the value, efficiency and convenience in use of sad-irons of the class to which my invention pertains.

One purpose of my invention is to provide 25 a structure affording an improved combustion chamber so that the iron may be properly heated, and another purpose of the invention is to enable the convenient cleaning-out of said chamber whenever desired.

30 A further purpose of the invention is to provide means for detachably securing the upper part of the iron to the lower part thereof in various adjustments so as to regulate the drafts through the combustion chamber.

Another object of the invention is to provide 35 an adequate body of metal, without undue weight, in the bottom of the iron so that the iron may not with undue rapidity become cooled on its ironing face, especially while ironing damp fabrics.

The invention will be fully understood 40 from the detailed description hereinafter presented, reference being had to the accompanying drawings, in which:

Figure 1 is a top view of the lower portion or section of the iron of my invention; Fig. 2 is a central vertical longitudinal section of the complete iron; Fig. 3 is a central vertical 45 transverse section of the same on the dotted line 3—3 of Fig. 2; Fig. 4 is a detached top view of the mechanism carried by the top section of the iron for securing it to the lower section thereof; Fig. 5 is a top view of

the complete iron, and Fig. 6 is a detached 55 sectional view through a portion of the top section of the iron on the dotted line 6—6 of Fig. 5.

In the drawings 10 designates the lower section of the iron, 11 the top section thereof, 60 and 12 the handle connected with said top section by suitable standards 13. The top section 11 comprises a top-plate 14, a downwardly encompassing edge-flange 15, and outlet flues 16 provided at opposite sides of 65 the front and rear ends of said top section and formed by upwardly and outwardly curved portions 17 of said top-plate 14 extending above the adjacent portions of the flange 15 and leaving openings above said 70 flange to constitute said flues, as indicated in Fig. 6. The top-section 11 carries the means for connecting it with the lower section 10, and these means comprise two suitably spaced - apart transverse bars 18 pivotally 75 mounted, on end trunnions 19, in the sides of the flange 15, arms 20 extending downwardly from said bars 18 and having oppositely extending dogs 21 at their lower ends, a longitudinal bar 22 below the bars 18 and 80 having in openings in its ends transverse rods 23, inclined fingers 24 extending downwardly and outwardly from the bars 18 and below the rods 23 (Fig. 2), and a central pivot-pin 25 connected with the bar 22 and 85 having at its upper end a button 26 preferably provided with a hinged loop-handle 27.

The top 14 of the upper iron-section 11 is provided with a longitudinal slot 28 adapted to receive the button 26, which when it is in line with said slot may be depressed into or pulled upwardly through the same. When the button 26 is pressed downwardly into the slot 28, it depresses the bar 22 and rods 23, causing said rods to press downwardly 95 against the fingers 24 and thereby compelling the bars 18 and arms 20 to rock downwardly and inwardly toward each other, with the result of releasing the dogs 21 from the lower section 10 of the iron and leaving 100 the upper section 11 free to be lifted from said section 10 or adjusted upwardly or downwardly thereon. When the button 26 is pulled upwardly through the slot 28 it elevates the bar 22 against the bars 18 and 105 causes said bars and their arms 20 to rock outwardly from each other, with the result that the dogs 21 are forced into engagement

with the lower iron-section 10, for connecting the upper and lower sections of the iron together. After the button 26 has been pulled upwardly through the slot 28 for connecting together the upper and lower sections of the iron, said button is given a one-quarter turn to cross the slot 28 and lock the dogs 21 in their engaging relation to the lower iron-section 10. The button 26 is provided with a pivoted loop 27 for convenience in manipulating it, and said loop is pivotally connected with the button 26 so that when the button is across the slot 28 the loop may be folded downwardly out of the way of the hand of the person using the iron. The arms 20 are thus rocked toward each other to release the upper section 11 from the lower section 10, and they are rocked from each other to connect said sections together, and as shown in Figs. 3 and 4 there are two arms 21 at each side of the iron.

The lower section 10 of the iron is a hollow shell comprising a bottom 28, vertical sides 29 and interior frame 30, and the top section 11 covers the section 10 and its sides 15 pass downwardly over the sides 29 of the section 10. The sides 29 of the lower section 10 are recessed or cut away at opposite sides of the section, as at 31, to receive the 30 downwardly extending arms 20, and at the opposite edges of the recesses 31 the sides 29 are formed with a series of serrations or teeth 32 to interlock with the dogs 21 of said arms. When the top section 11 is applied to the lower section 10, the dogs 21 will be interlocked with such of the teeth 32 as will leave the top section in the desired relation to the lower section, the series of teeth 32 affording a means of adjustment 40 enabling the top section to be elevated or lowered in accordance with the amount of air-draft to be permitted through the interior combustion chamber of the iron. The lower section 10 is not only recessed at its 45 opposite sides, as at 31, but is also recessed at both ends, as at 33, and these recesses 31, 33 are located at a suitable elevation above the bottom of the section 10 and afford draft spaces for the air required for combustion, 50 which spaces may be varied in size by the vertical adjustment of the upper section 11 on the lower section 10, the flange or skirt 15 of the top section 11 serving to more or less cover the recesses 31, 33 as said section 55 is adjusted upwardly or downwardly.

The bottom 28 of the lower cast section 10 is formed on its upper surface with a series of vertical somewhat cone-shaped studs 34 which are distributed over and integral with 60 said surface. The studs 34 are beneficial in several respects, one being that the fuel is placed upon them and that they allow the air to find its way below the fuel. The studs 34 are also of advantage because they hold 65 the heat and prevent the bottom 28 from

cooling with undue rapidity, thus allowing the iron to be constantly used a greater length of time. Self-heating irons, especially when used on damp clothes, give off their heat with some rapidity, the bottom 70 of the iron being comparatively thin. The studs 34 not only serve to support the fuel and aid in securing proper combustion but afford an increased body of metal in the bottom of the iron without creating undue 75 weight in the same or unduly reducing the capacity of the fuel chamber. The shell 30 extends entirely around the inner walls of the lower section 10, as shown in Figs. 1 and 2, and at its opposite sides, adjacent to 80 the recesses 31 in the sides of said section 10, the body of the shell inclines downwardly and inwardly, forming shields 35 which while preventing the spilling of the fuel through said recesses do not obstruct the air 85 draft through the same, as may be seen by reference to Fig. 3. The lower edges of the shields 35 are formed with a series of recesses 36, which form draft passages. The sides of the shell 30, at the front and rear 90 of the shields 35 are cut away, as at 37, and the front and rear ends of the shell are formed with draft passages 38. The shell 30 may be made of sheet metal and sprung into the lower section 10 or it may be riveted 95 to said section or left free to be readily lifted therefrom. The shell 30 guards the recesses 31, 33 without obstructing the drafts through the same and by being cut-away or recessed at 37 avoids occupying undue space 100 in the combustion chamber of the iron.

In the employment of the iron the top section 11 is removed and the fuel placed in the bottom section 10, as usual, and in restoring the top section to the section 10, 105 said top-section will be adjusted downwardly to the extent desired but leaving the lower portions of the side recesses 31 and end recesses 33 uncovered for the passage of air through the same. The draft passages 110 at 31 and 33 may at any time be varied by adjusting the top-section 11 vertically with relation to the lower section 10, so as to modify the draft through the combustion chamber as the conditions therein might require. The draft outlet from the combustion chamber is through the flues 16. The recesses 31, 33 at opposite sides and ends of the iron not only provide for the adequate admission of the air but enable the ash to 115 be blown, from time to time as may be desirable, from the combustion chamber.

What I claim as my invention and desire to secure by Letters Patent, is:

1. A sad-iron comprising a hollow lower 125 shell section having a bottom 28 and vertical sides 29 which are recessed to admit air, and a hollow upper section having a top 14 and a downwardly encompassing edge-flange 15 to telescope over said vertical 130

sides, combined with means for detachably securing the upper to the lower section in vertically adjusted relation so that the said flange on the upper section may more or less cover the inlet for air to the chamber within the iron, said upper section having a flue outlet; substantially as set forth.

2. A sad-iron comprising a hollow lower shell section having a bottom 28 and vertical sides 29 which are recessed at the ends and sides of the iron to admit air, and a hollow upper section having a top 14 and a downwardly encompassing edge-flange 15 to telescope over said vertical sides, combined with means for detachably securing the upper to the lower section in vertically adjusted relation so that the said flange on the upper section may more or less cover the side and end air inlets to the chamber within the iron, the iron being pointed at both ends, and said upper section having outlet flues at both sides of each end; substantially as set forth.

3. A sad-iron comprising a hollow lower shell section having a bottom 28 and vertical sides 29 which are recessed to admit air, and a hollow upper section having a top 14 and a downwardly encompassing edge-flange 15 to telescope over said vertical sides, combined with means for detachably securing the upper to the lower section in vertically adjusted relation so that the said flange on the upper section may more or less cover the inlet for air to the chamber within the iron, said upper section having a flue outlet, and said lower section having on the upper surface of its bottom and integral therewith a series of fuel supporting lugs 34; substantially as set forth.

4. A sad-iron comprising a hollow lower section having draft recesses at its sides and ends, and a hollow upper section having outlet flues, combined with means for detachably securing the upper to the lower section in adjusted relation so as to vary the exposure of said draft recesses; substantially as set forth.

5. A sad-iron comprising a hollow lower shell section having a bottom 28 and vertical sides 29 which are recessed at the ends and sides of the iron to admit air, a hollow upper section having outlet flues and a downwardly encompassing edge flange 15 to telescope over said vertical sides, and an inner shell 30 within said lower section and recessed in line with and affording shields for the air inlets, combined with means for detachably securing the upper to the lower section in vertically adjusted relation so that said flange 15 may more or less cover the side and end air inlets in the lower section; substantially as set forth.

6. A sad-iron comprising a hollow lower section having in its opposite sides vertical recesses, a hollow upper section to pass

downwardly upon and encompass said lower section, and means carried by the upper section for detachably securing the same to the lower section and comprising pivotally mounted arms 20 adapted at their lower ends 70 to interlock with the lower section at the edges of said recesses, means for causing said arms to swing free of the lower section and means for locking said arms in engagement with said lower section; substantially as set 75 forth.

7. A sad-iron comprising a hollow lower section having in its sides vertical recesses whose side edges are serrated, a hollow upper section to pass downwardly upon and 80 encompass said lower section, and means carried by the upper section for detachably securing the same in adjusted relation to the lower section and comprising pivotally mounted arms 20 having dogs at their lower 85 ends to engage said serrations, means for causing said dogs to swing free of said serrations and means for locking said dogs in engagement with said serrations; substantially as set forth. 90

8. A sad-iron comprising a hollow lower section having in its sides vertical recesses whose side edges are serrated, a hollow upper section to pass downwardly upon and encompass said lower section, and means carried by the upper section for detachably securing the same in adjusted relation to the lower section and comprising transverse pivotally mounted bars 18 having depending arms 20 provided at their lower ends with 100 dogs to engage said serrations, a longitudinal bar 22 extending below said bars 18 and having a swiveled button 26 adapted to enter and be turned across a slot 28 in the top of the iron, and means on said bar 22 for causing, when said bar is depressed, said arms to swing free of said serrations, said bar 22 when elevated being adapted to press against said bars 18 and force said dogs into engagement with said serrations; substantially 110 as set forth.

9. A sad-iron comprising a hollow lower section having in its sides vertical recesses whose side edges are serrated, a hollow upper section to pass downwardly upon and 115 encompass said lower section, and means carried by the upper section for detachably securing the same in adjusted relation to the lower section and comprising transverse pivotally mounted bars 18 having depending arms 20 provided at their lower ends with dogs to engage said serrations, a longitudinal bar 22 extending below said bars 18 and having a swiveled button 26 adapted to enter and be turned across a slot 28 in 120 the top of the iron, downwardly and outwardly inclined fingers 24 carried by the bars 18, and transverse rods 23 carried by the bar 22 above said fingers, said rods when the bar 22 is depressed serving to act against 125 130

said fingers and cause the arms 20 to swing free of said serrations, and said bar 22 when elevated being adapted to press against said bars 18 and force said dogs into engagement with said serrations; substantially as set forth.

Signed at New York city, in the county of

New York and State of New York, this 26th day of January A. D. 1910.
